SODA STRAW DISPENSER AND THE LIKE

Filed July 26, 1947

Inventor
JAMES H. BUTLER

Earl Chapman
Attorney

the straws to be dispensed. In alignment with the extreme ends of this egress slot on the inner sides of each support 1 and 2, there is a track-way or sideway element 22, each of which is provided at its forward end with a turned portion 23. These turned ends are designed to act as straw stops and conveniently support each straw, as dispensed, so that a customer can easily grasp it and remove it.

Just above the slot, there is an elongated platform, 24, which is provided with the cutaway portions or slots 25 and 26, the stop ends of which limit the upward movement of the fingers or arms 16, note Fig. 5. This platform is spaced from the shoulder 19 so as to provide an elongated drop opening 21' which is just large enough to freely drop therethrough any one of the straws 27, a straw 27' being shown in position, in dotted lines, ready for the arms 16 (in dotted lines) to eject it through the under passage and out through the slot 21. Any suitable stop like the pins 13' may be provided to limit the downward movement of the levers 15. It is while the arms are retracted, or the lever in a downward sufficiently pressed position, that a single straw is free to fall easily into the lower chamber 27 of the device and be ready for ejection into the guideways 22, when the arms 16 start on their return to their uppermost position, as shown in Figure 4 of the drawings. The arms are returned to their top position when the levers 15 are free, that is, released by the operator. The means for returning the arms automatically to their original position, as well as the levers, is the spring item 28.

It should now be apparent that a new and convenient straw dispenser has been provided which is a sanitary and clean device, and which, in all respects, is simple in construction, but nevertheless, sturdy so as to give long and dependable service.

It is, of course, understood that various changes and modifications may be made in the details of form, style, design, and construction of the whole or any part of the specifically described embodiment of this invention without departing from the spirit thereof; such changes and modifications being within the scope of the following claims.

I claim:

1. In a soda fountain straw dispenser and the like, said dispenser including a hollow housing with its ends closed by end supporting members, a chamber in the housing having cylindrical walls, a shaft through the chamber supported by the end members, extending arms on the shaft for supporting straws above the bottom of the chamber, an egress opening along a bottom por-

tion of the chamber, arm stop means at the bottom of the chamber, cantilever means extending from just above the egress opening to just short of the stop means and thus providing a straw drop opening, and a passage beneath the cantilever means connecting the drop opening with the egress opening.

2. In a dispenser device for straws, toothpicks, swabbing sticks and the like, the device including a hollow housing with its ends closed by end supporting members, the housing providing a chamber having curved walls, a shaft extending through the chamber and having its ends supported by the end members, radial arms fixed to the shaft and extending therefrom which support a plurality of straws above the bottom of the chamber, an elongated egress opening along a lower portion of the chamber wall which is substantially parallel with the shaft, arm stop means at the bottom of the chamber at a lower level than the egress opening, a cantilever wall means extending from just above the egress opening to a position just short of the stop means to provide an elongated straw-drop opening, and an elongated passage beneath the cantilever wall means connecting the straw-drop opening with the egress opening.

3. The device recited in claim 2 wherein the opposed inner surface of each end supporting member is provided with a ledge which terminates into a forward turned-up portion; the two ledges cooperating to support and guide each straw from the egress opening and bring it to rest in a spanning position.

4. The device recited in claim 2 wherein the shaft is provided with extended radially directed arm-like lift members fixed thereto and angularly spaced more than 120° from the arms to provide a greater more useful straw carrying capacity within the chamber.
